UNITED STATES PATENT OFFICE.

EDWARD MELVILLE HUGGINS, OF NEW YORK, N. Y.

JOLT RAMMING-MACHINE.

1,242,351.

Specification of Letters Patent.

Patented Oct. 9, 1917.

Application filed December 24, 1914. Serial No. 878,981.

To all whom it may concern:

Be it known that I, EDWARD MELVILLE HUGGINS, a citizen of the United States, residing at New York, in the county and State of New York, have invented certain new and useful Improvements in Jolt Ramming-Machines, of which the following is a specification.

This invention relates to jolt ramming machines for ramming sand molds and the like, and it has for one of its primary objects the provision of an improved arrangement of jolt ramming machine wherein wear on the parts is automatically compensated for, thereby adding to the general efficiency of the machine and the length of its life. Another object of my invention resides in the provision of a novel impact or anvil surface which is so arranged that the force of the impact is equally distributed at all times, regardless of any wear of the parts.

The foregoing together with such other objects as may hereinafter appear, or are incident to my invention, I obtain by means of a construction which I have illustrated in preferred form in the accompanying drawing, the figure being a partial side elevation and vertical section of a jolt ramming machine embodying my improved features.

Referring now to the general arrangement of parts it will be seen that the machine comprises the usual base 7 to which is bolted the cylinder 8 in which is mounted a plunger 9 having a flanged top 10. Secured to the top 10 is the mold table 11. The plunger 9 is preferably fluid actuated but any other suitable operating means may be employed. In the present embodiment the pipes 12 and 13 indicate the inlet and exhaust pipes respectively, the flow of fluid pressure being controlled in any desired manner.

The cylinder 8 is strengthened by a plurality of vertically extending radial ribs 14 and is further provided at the top with an annular rib or shoulder 15, which in effect constitutes an impact shoulder or anvil. It will be noted that the upper surface 15^a is curved from the outer upper edge downward and inward toward the center of the machine. Resting on such concaved surface is an impact ring 16 preferably of metal, the lower surface of which is convex and is formed on the same radius of curvature as that of the surface 15^a upon which it rests. The upper surface of the impact ring is

preferably flat and is engaged by the under surface of the flanged top 10 when the plunger 9 is in lower or bottom position.

A plurality of pins 17 are mounted in the impact ring 16 being preferably riveted in place. The pins depend from the ring and project downwardly through the apertures 18 formed in the shoulder 15, such apertures being of a larger diameter than that of the pins so that the latter have a loose fit in the apertures. Adjacent the bottom, the pins 17 have shoulders 19 and the ends of the pins are threaded to receive the nuts 20 which serve to lock the washers 20' in position against the shoulders or collars 19. Interposed between the washers 20' and the under face of the shoulder 15 are springs 22, which normally tend to hold the impact ring 16 in engagement with the shoulder 15. Only one of the pins 17 and its associated parts are shown but it will readily be understood that any suitable number may be employed. The plunger is steadied and guided in its movement by means of guide rods 23 which are bolted to the flanged top 10 and have sliding engagement with the apertured guide lugs 24 formed on the cylinder 8. The joint between the impact ring and the shoulder 15 is protected by the annular guard ring 25 which is bolted to the under face of the top 10, preferably by means of the same bolts 26 which serve to detachably secure the table 11 to the plunger top.

It will be seen from the foregoing that the joint between the impact ring and the shoulder is in effect a ball joint which permits of a shifting of the impact ring with respect to the shoulder 15, this shifting movement being permitted by virtue of the loose fit of the pins 17 in the apertures 18. In cases of wear of the parts, or in other conditions of service, the impact ring will shift during operation so as to provide a true impact surface and thus secure a uniform and equal distribution of the force of the impact, thus greatly increasing the efficiency of the machine. The impact ring will freely shift through a limited range of movement and it is at the same time yieldingly held in proper engagement with the shoulder by means of the springs 22. It will be obvious that the curved impact surface may be arranged at another part of the machine, but I prefer to locate it at the top of the cylinder as shown, adjacent the outer

edge of the top of the plunger at which point it operates in the most advantageous manner.

The advantages incident to my improved apparatus will be apparent to those skilled in the art, and it will be obvious that considerable variations may be made in the actual structure employed without departing from the spirit of the invention.

10 By virtue of its being mounted for automatically shifting compensatory movement, the impact ring may be termed a "floating" impact member.

What I claim is:

15 1. In a jolt ramming machine, a vertically movable plunger, and an anvil portion surrounding the plunger adapted to receive the impact of the plunger and having a uniformly curved impact surface, and a member interposed between the plunger and the anvil carried on said curved impact surface.

20 2. In a jolt ramming machine, a vertically movable plunger, an anvil having a curved impact surface, and a floating impact member carried on said surface adapted to receive the impact of the plunger.

25 3. In a jolt ramming machine, a vertically movable plunger, an anvil, and a compensating floating impact member adapted to receive the impact of the plunger and automatically shift to distribute the force of the impact substantially equally.

30 4. In a jolt ramming machine, a cylinder having an anvil portion, a plunger in said cylinder carrying a mold table, and a compensating floating impact ring on the anvil portion adapted to receive the impact of the plunger and automatically shift to distribute the force of the impact uniformly.

35 5. In a jolt ramming machine, a cylinder having an annular anvil provided with a curved impact surface, a floating impact ring carried on said surface, and a plunger in the cylinder adapted to impact on said ring.

40 6. In a jolt ramming machine, a cylinder having an annular concave anvil, a convex impact ring loosely carried on the anvil on

the concave surface thereof, and a plunger in the cylinder adapted to impact on the 50 ring.

7. In a jolt ramming machine, a cylinder having an annular anvil provided with a curved impact surface, a floating impact ring carried on said surface, a plunger in the cylinder adapted to impact on said ring, and means yieldingly holding the ring in engagement with the anvil.

8. In a jolt ramming machine, the combination of a reciprocating member having an impact surface, and an impact receiving member automatically alining with the said impact surface.

9. In a jolt ramming machine, a plunger, a table carried on the plunger, a two-part 65 impact anvil adjacent the table the parts whereof have relative movement and on which the plunger impacts, and a curtain protecting the joint between the parts of the anvil.

70 10. A jolt ramming machine comprising in combination, a cylinder having an anvil portion, a reciprocating member, an impact member having a curved face carried upon said anvil portion adapted to receive the 75 impact of the reciprocating member, inter-engaging means on the impact member and anvil portion serving to position the impact member thereon but permitting a limited relative movement of the impact 80 member with respect to the anvil portion, and a plunger in the cylinder adapted to impact on the impact member.

11. In a jolt ramming machine, the combination of impacting members, the impact 85 surfaces of which are inversely sloped to co-act to automatically distribute the force of the impact evenly.

In testimony whereof I have hereunto signed my name in the presence of the two 90 subscribed witnesses.

E. MELVILLE HUGGINS.
